UNITED STATES PATENT OFFICE

111,603

DESIGN FOR LACE

Emil Katz, New York, N. Y.

Application September 8, 1938, Serial No. 79,784

Term of patent 3½ years

To all whom it may concern:

Be it known that I, Emil Katz, a citizen of the United States and a resident of the city of New York, in the county of Kings and State of New York, have invented a new, original, and ornamental Design for Lace, of which the following is a specification, reference being had to the accompanying drawing, constituting a part thereof.

The figure is a plan view of a piece of the lace showing my new design.

I claim:

The ornamental design for lace, substantially as shown.

EMIL KATZ.
